CLAIM

The ornamental design for an escalator handrail entry housing, as shown and described.

DESCRIPTION

FIG. 1 is a perspective view of the escalator handrail entry housing showing the left side and top;

FIG. 2 is an enlarged view of FIG. 1;

FIG. 3 is a top view of the escalator handrail entry housing; and,

FIG. 4 is perspective view of the escalator handrail entry housing showing the front and right sides.

The broken lines shown in the drawings illustrate the environment upon which the article is mounted and are not a part of the claimed design.

The undisclosed rear is open and unornamented.
